UNITED STATES PATENT OFFICE

HAROLD W. HOLMES, OF DETROIT, MICHIGAN, ASSIGNOR, BY MESNE ASSIGNMENTS,
TO CINCINNATI GRINDERS INCORPORATED, OF CINCINNATI, OHIO, A CORPORA-
TION OF OHIO

CENTERLESS GRINDING MACHINE

Application filed February 10, 1926, Serial No. 87,406. Renewed November 19, 1928.

This invention relates to grinding machines, and more particularly to one adapted for grinding special shapes of round work, such as a cylinder having a shoulder or enlargement thereon, which is ground and rotated between and respectively by a rapidly rotated grinding wheel and a slowly rotated work regulating wheel.

It has been proposed heretofore to grind cylindrical bodies in a centerless grinding machine having a rapidly rotated grinding wheel and a slowly rotated work regulating wheel between which the work is positioned during the grinding operation. This machine has been satisfactory for certain types of cylindrical work but has not been readily and easily adaptable for grinding work of special shapes, such as certain types of shouldered pieces of different diameters, lengths, and weights, on a satisfactory production basis on account of the difficulty of handling the work in the machine.

It is an object of the invention to provide a machine of this general type embodying certain features to facilitate the grinding of certain types of cylindrical work which cannot be passed through the machine axially in contact with the grinding wheel, and to make possible the grinding of such work by a direct in-feed cut with a high degree of accuracy, speed and increased efficiency so that successive pieces of work will be ground in exactly the same manner and to substantially the same uniform size.

A further object is the provision of a centerless grinding machine constructed in such a manner as to be easily adapted for grinding a large variety of special types of cylindrical work of varying length, diameter, and weight, and which may be operated periodically or automatically to grind successive work pieces, and thereby render the grinding machine useful and advantageous in various fields where it has been impossible heretofore to use it.

In grinding shouldered work it has been necessary for the operator to place the work between the wheels accurately in a position for grinding. In so doing there has been great danger of injury to the operator by

accidental contact between his hand and one of the wheels. It is a still further object of the invention to provide mechanisms in a grinding machine of this general type whereby work pieces may be presented in a position for accurate grinding in such a manner as to minimize the danger of injury to the operator and such that successive work pieces may be ground in a systematic manner, and whereby the grinding machine may be utilized to the best advantage in the interest of increased production and economy of time.

In accordance with certain features of the invention I provide a centerless grinding machine for grinding special types of cylindrical work while positioned or held between oppositely disposed work-holding members or blades and in contact with a rapidly rotated grinding wheel and a slowly rotated work regulating wheel arranged as in any one of the now well known types of centerless grinding machines. Preferably, the wheels are so mounted that one wheel, such as the grinding wheel, may be moved periodically by a suitable mechanism towards and away from the other and preferably so that the grinding wheel may be directly and positively fed into or toward the work. In order that the machine may be readily and easily adaptable for grinding work pieces of different diameter or length and also to achieve certain other advantages I provide a mechanism arranged to move one of the work-holding members or blades, preferably through positions parallel to the work axis, towards the work into approximate contact therewith while the movable wheel is away from the other and then into contact with the work during grinding and thereafter withdrawn while the two wheels are separated to permit discharge of ground work. In the machine illustrated in the accompanying drawings, the ground work is discharged laterally preferably by rolling it off in the direction of rotation of the work regulating wheel.

The work may be placed in a grinding position between the wheels by hand, but in accordance with the preferred embodiment of my invention I provide a mechanism adapted to move a work piece an invariable distance in

an axial direction into a position between the wheels for grinding. This mechanism is preferably arranged to operate in timed relation to the wheel and work-holding blade movements, so as to move a work piece between the wheels when they are separated and when the movable blade is in approximate grinding position. If desired, and preferably, the wheel and work-holding blade movements may be operated by power connections which may be manually controlled by a device adapted to connect the power with their respective actuating mechanisms and at the same time actuate the work moving mechanism to move a work piece between the wheels at a desired rate into a grinding position. The work moving mechanism may be constructed and arranged to withdraw automatically when the manual control device is moved to its original position so as to disconnect the power and stop the wheel and blade moving mechanisms at the end of one cycle, that is, after completion of the grinding operation and when the wheel and work-holding blade have moved away from the work to permit discharge thereof and the blade returned to an approximate grinding position.

Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings, in which is shown a preferred embodiment of my invention,

Fig. 1 is an elevational view from the right hand side, with parts broken away, of a centerless grinding machine embodying the invention;

Fig. 2 is a detached perspective view of the work moving mechanism and the manual control device connected therewith;

Fig. 3 is a detail view of a portion of the work moving mechanism;

Fig. 4 is a detached perspective view of the power connection to the movable work-holding member;

Fig. 5 is a detail perspective view of the tripper mechanism;

Fig. 6 is a sectional view along the line 6—6 of Fig. 1;

Fig. 7 is a sectional elevational view through the trunnion in which the grinding wheel spindle is mounted;

Figs. 8 to 10 inclusive are diagrammatic views showing the positions of the work and various mechanisms of the machine during its operation; and

Fig. 11 is a diagrammatic view showing the shape and relative positions of the cams con-

trolling the movements of the grinding wheel and the front blade or work-holding member.

The apparatus illustrated in the drawings is adapted for semi-automatic operation but, as will be made clear hereinafter, may be operated in a fully automatic manner. The invention although broader in its scope is illustrated as embodying an arrangement in which a work regulating wheel is arranged beneath and is peripherally opposed to the grinding wheel. The apparatus includes a frame 10 (Fig. 1) within which is mounted a grinding wheel spindle 11 carrying a grinding wheel 12. The grinding wheel spindle 11 is rotated rapidly from a suitable source of power by a belt 13 passing over a pulley 14 secured upon the spindle 11.

A column 15 may be moved vertically within a cylindrical portion 16 of the frame 10, to which it is splined, by means of a hand wheel (not shown) keyed to the shaft of a worm 17 meshing with a worm wheel 18 keyed to a screw shaft 19 engaging threads in a boss 20 integral with or otherwise appropriately secured to the frame. A work regulating wheel 23 is mounted, beneath and peripherally opposed to the grinding wheel, upon a spindle 24 for rotation in suitable bearings (not shown) and is substantially enclosed within the bearing casing 25 supported upon the block 26 mounted upon the upper portion of the column 15; the regulating wheel may be rotated relatively slowly from any suitable source of power, such as a motor 27 connected directly to a shaft 28 having a worm 29 thereon meshing with a worm wheel 30 upon the regulating wheel spindle 24.

An auxiliary frame 33 fixed on the column 15 extends upwardly in the rear (to the right, as viewed in Fig. 1) of the regulating wheel 23. A work holding member or blade 34 is slidably mounted in a carriage 35 having a portion 36 adapted to move in the vertical slideways 37 in the frame 33. The carriage 35 may be moved vertically by means of a pinion 38 meshing with the rack 39 secured upon the carriage 35. The work-holding member 34 may be suitably adjusted and maintained with its work-contacting or guiding edge parallel to the axis of the grinding wheel by means of a pair of pins 40, each slidably supported and engaging the member 34 at one end and a cam 41 at the other end, thereby assuring that the guiding or work-engaging surface of the work-holding member 34 is maintained parallel to itself or to the axis of the grinding wheel as it is moved in and out for use with work of different sizes. The arrangement of the cams 41 and coacting parts is not per se my invention and is described in detail and claimed in the co-pending application Serial No. 91,861 of Fred M. Kern and Ernest R. Seward, filed March 3, 1926, and to that application refer-

ence may be had for further details of the construction and action thereof. A water pan 42 is mounted upon the top of the column 15 and is secured to the block 26 by means of bolts 43.

5 The grinding wheel spindle 11 and the work regulating wheel spindle 24 may bear a fixed relation to each other but I prefer to construct the machine so that one of the 10 wheels may be moved towards or away from the other wheel to facilitate feeding work between the wheels and subsequently discharging the ground work. This may be accomplished by mounting the grinding wheel 15 so it may be moved periodically toward and away from the other wheel. Thus, the grinding wheel spindle 11 carried in a tapered split bearing 45 (Fig. 6) is adjustably mounted within the trunnion 46 (Fig. 7) and has its 20 axis located eccentric to that of the trunnion. The latter has a cylindrical bearing surface 47 mounted for rotative oscillation about its axis in the frame 10 (see Figs. 6 and 7) and is provided with a rearwardly extending arm 25 48 having an adjustable roller 49 positioned therein adapted to ride upon an arm 50. The roller 49 is held by a member 53 which is adapted to be moved within a slot 54 in the arm 48 by means of an adjusting screw 55. 30 The arm 50 is pivoted at one end to turn about a shaft 56 and has a cam roller 57 at the other end adapted to ride upon the peripheral surface of a cam 58 fixed upon the cam shaft 59. The inter-relation and coaction of the arm 48 35 with the arm 50 and immediately associated parts, whereby a wide variability of the action of the fixed cam 58 may be achieved by varying the position of the roller 49 lengthwise of the arm 50, are not per se my 40 invention but permit the achievement, in coaction with the other parts of the apparatus herein described, of many important advantages, and they are described in detail and claimed in the co-pending application 45 Serial No. 85,790 of Fred M. Kern, filed February 3, 1926, and to that application reference may be had for further details of the construction and action thereof. A relatively heavy weight 60 (Fig. 1) is suspended 50 by a rod 61 from the end of the arm 48 and serves to hold the cam follower 57 upon the cam 58.

The lateral thrust on the grinding wheel spindle 11 due to the pull of belt 13 upon 55 pulley 14 is taken by a roller race 62 (Fig. 6) suitably positioned in the trunnion 46 as illustrated. The pulley 14 is secured upon one tapered end of the grinding wheel spindle 11 by means of a nut 63, and the grinding 60 wheel 12 is secured upon the other end by means of a nut 64.

In order that the grinding wheel may be shifted axially through a suitable distance to 65 eliminate grain markings, the spindle 11 is mounted for reciprocation lengthwise

through the bearing 45, the bearing 62 being adapted to move therewith. This movement is caused, preferably, by a cam connection to a rocking arm and yoke to the spindle. As illustrated, the spindle has a yoke collar 70 75 65 (Fig. 6) fixed thereon and provided with a movable bushing 66 having a groove for the insertion of a yoke 67, which is keyed to a shaft 68 and supported for rocking movement in a bearing in the trunnion 46, as shown in Fig. 7. A crank arm 70 is keyed to the outer 80 end of the shaft 68 and is provided with a cam roller 71 which is adapted to engage the radial face of a cam 72 mounted upon the camshaft 59. The radial face is provided with a raised portion 73, suitably placed thereon to move the grinding wheel spindle axially during grinding of a work piece. Preferably, I provide but one raised portion 73, and the remainder of the cam face is 85 plane so that toward the end of the grinding operation the wheel will be given a single quick, short, axial movement to smooth over the work surface. The arm 70 is held by suitable means, such as spring (not shown), 90 so that the cam roller presses against the cam face, and the wheel 12, as in the preferred embodiment just noted is held in one position except as moved by the raised portion on the cam.

95 Turning now to Figs. 1 and 4 of the drawings, a U-shaped member 75 is mounted to swing about a horizontal pivot 76 secured in a bracket 77 integral with a plate 78 secured to a flat portion of the block 26 by means of bolts 79. The distance that the U-shaped member 75 may swing in one direction may be adjustably limited by means of an adjustable stop screw 80 (see Fig. 4). A front work-holding member or blade 83 is held, by bolts 84, in a groove 85 on a fixture 86 which is adjustably mounted upon the front arm of the U-shaped member 75 by means of bolts 87 passing through a slot 88 in the fixture. The fixture 86 is provided with an opening 89 which extends to a connection 90 for a pipe 91 so that a suitable liquid or coolant may be supplied over the top of the member 83 directly upon the work being ground.

100 In accordance with the preferred embodiment of the invention, the member 75 is actuated by a cam 95 mounted upon the camshaft 59 (Figs. 1 and 4). An arm 96 is keyed at one end to a shaft 97 and is provided at its other end with a cam roller 98 adapted to engage 105 the peripheral surface of the cam 95. A second arm 99 is keyed at one end to the shaft 97 and is provided at its other end with a block 100 pivoted in the arm 99 to slidably engage a rod 101. The rod 101 is pivotally 110 secured at one end to the movable member 75 and is threaded at the other end for adjustable nuts 102 (Fig. 1) which holds a spring 103 upon the rod and in contact with the block 100. A spring 104 (Fig. 1) is fastened be- 115 120 125 130

tween the front of the water pan 42 and the fixture 86 upon the front arm of member 75 and, in tending to swing member 75 in counter-clockwise direction, acts to maintain the cam roller 98 in contact with the peripheral surface of the cam 95.

The camshaft 59 may be rotated by means of a worm 108 (Fig. 1) on a shaft 109 meshing with a worm wheel 110 fixed upon the camshaft. The shaft 109 may be rotated from any appropriate source of power by means of a belt 111 passing over a clutch pulley 112 on the shaft 109.

One of the wheels, such as the grinding wheel, may be moved towards and away from the other at any desired rate and in timed relation with the movement of the U-shaped member 75 and associated parts. For this purpose suitable means may be provided for 20 rotating the drive shaft 109 and consequently the camshaft 59 at different speeds. Thus, a belt 115, driven from any appropriate source of power, passing over a pulley 116 may be employed to rotate a shaft 117 at any desired speed. The power thus applied to the shaft 25 117 may be transmitted to a shaft 118 and consequently to the belt 111 through the instrumentality of a belt 119 connecting cone pulleys 120 and 121. A suitable toothed clutch 122, which is splined to the shaft 109, is provided for connecting the clutch pulley 30 112 with the worm 108.

The clutch 122 may be moved to engage or disengage the pulley 112 by a manually controlled device. Such a device (Figs. 1 and 35 5) may include a clutch yoke having hubs 125 and 126 pivotally mounted upon the shaft 97. An arm 127 extends rearwardly from the hub 125 and is provided with a V-shaped 40 projection 128 on its end (Fig. 1). The projection 128 is adapted to contact with the V-shaped end projection 129 on a pin 130 slidably mounted in a boss 131 in the frame of the machine. A spring 132 maintains a contact 45 between the V-surfaces of the end projections 128 and 129. A fork 133 extends downwardly and forwardly from the hubs 125 and 126 and carries a pair of pins 134 (Fig. 5) adapted to ride in a groove 135 in the clutch collar. A double link 136 projects forwardly 50 and is secured at one end to the fork 133 and supported at the other end by a downwardly extending arm 137 of a bell crank 138 pivotally mounted upon the shaft 56. A vertically positioned rod 140 having a slot 141 is mounted to slide upon a pin 142 in the forward end of the double link 136. The rod is secured at its lower end to a link 143 (Fig. 1) which is keyed to a shaft 144 suspended in 60 the frame of the machine for rotary movement. A clutch operating lever 145 is secured upon the shaft 144 so that movement to the left, as viewed in Fig. 1, will move the rod 140 upward relative to the double link 65 136 (Fig. 5) to strike against the forwardly

extending arm 146 of the bell crank 138, and thereby turn the bell crank to move the double link 136 and the fork 133 forward (that is, towards the front of the machine) and bring the clutch 122 into engagement with the pulley 112 to rotate the camshaft 59. The lever 145 (Fig. 1) is provided with a spring plunger 148 which may engage openings 149 in a plate 150 secured upon the outside of the frame of the machine. The plate 150 may be provided also with a pair of stops 151 (Fig. 1).

When it is desired to stop the machine automatically at the end of a single cycle of operations, the lever 145 may be moved so as to bring the rod 140 to a higher position, whereby the projection 153 (Fig. 5) will be positioned in an appropriate part of the path circumscribed by a projection 154 on a tripper cam 155, which is secured to the camshaft 59. With the rod 140 in such a position, the projection 154 of cam 155 engages the projection 153 on the rod 140 to move the double link 136 horizontally (to the right, as viewed in Fig. 5) an amount sufficient to disengage 90 the clutch 122 from the pulley 112.

In order to expedite the grinding of successive work pieces and to eliminate the danger of injuring the workmen, I provide a device for moving work axially preferably 95 an invariable distance between the wheels to an appropriate grinding position. A preferred form of device for this purpose comprises a horizontally disposed casing 158 (Figs. 1, 2, and 3) mounted on the right hand 100 side of the machine (the side seen in Fig. 1) to the water pan 42, parallel to the axis of the grinding wheel, by means of bolts 159 passing through slots 160 in a bracket 161. A plunger 163 (Fig. 3) is adapted to move 105 within the casing 158 between rollers 164, and is moved towards the wheels by means of a rope 165, secured at one end to an ear 166 on the plunger, passing over a pulley 167 to a bolt or hook 168 to which it is secured and which is adjustably mounted upon an 110 arm 169 on the lever 145 by means of a set screw 170. The plunger 163 is operated against the tension of a spring 171 (Fig. 3) secured at one end to a pin 172 in the plunger 115 and at the other end to a pin 173 (Fig. 2) in the casing. The position of rest of the plunger 163 may be varied by means of an adjustable stop screw 174, threaded in a projection 175 in the casing, engaging the ear 166 on the plunger 163. A work conveyor 176 is pivoted to turn about a pin 177 in the casing 158 and is normally held against an adjustable stop screw 178 by means of a leaf spring 179. The work conveyor 176 may be 120 of any construction suitable for the work, and that shown in the drawings (Figs. 2 and 3) is particularly adapted for receiving headed work pieces, such as shackle bolts. Thus, the shank of the bolt may rest upon 125 130

the projection 180 and the head of the bolt may rest in the V-shaped slideway 181 which has a groove 182 at its bottom. The plunger 163 is provided with a depending finger 183 (Fig. 3) which, when the plunger is moved to the right, as seen in Figs. 3 and 4 and hence towards the wheels, is adapted to engage a projection 184 in the groove 182 and thereby cause the conveyor 176 to turn about the pivot 177 so as to lower the projection 180 a sufficient distance to allow the plunger 163 to push the work on to the work regulating wheel 23 and between the work-holding members 34 and 83.

Considering now the operation of the machine, the grinding wheel 12 is rotated rapidly to give it a suitable grinding speed and in the direction indicated by the arrow (Figs. 1, 8, 9 and 10) from any appropriate source of power by means of a belt 13 passing over the pulley 14 on the grinding wheel spindle 11. The work regulating wheel 23 is rotated relatively slowly, in the direction indicated by the arrow, through shaft 28, worm 29 and worm wheel 30 by means of a motor 27. With the pulley 112 rotating at a desired speed, the camshaft 59 may be set in rotation by pulling the lever 145 to the left, as viewed in Fig. 1, which raises the rod 140 to strike 30 against the arm 146 of the bell crank 138. This throws the double link 136 forward (to the left in Figs. 1 and 5) and brings the clutch 122 into engagement with the pulley 112.

With the lever 145 in this position, it will be noted that the projection 153 on the rod 140 is above and out of the path circumscribed by the projection 154 on the tripper cam 155 so that the machine may operate 40 completely and continuously automatically. Thus, the camshaft 59 together with the cams 58, 72 and 95 thereon may rotate uniformly and continuously with the cam rollers 57, 71 and 98 in contact therewith respectively to actuate their respective mechanisms, namely, for moving the grinding wheel 12 towards and away from the work regulating wheel 23, for moving the U-shaped member 75 to carry the front work-holding 50 member or blade 83 cyclically towards and away from the work, and for reciprocating the grinding wheel axially during grinding of the work.

It will be noted that rotation of the cam 58 (Figs. 7, 11 and 1) raises and lowers the cam roller 57 to raise and lower the free end of the pivoted arm 50 which in turn raises and lowers the cam roller 49. The latitude of movement of the arm 48 may be reduced 60 or increased by adjusting the position of the cam roller 49 on the arm 48 by turning the adjusting screw 55 to move the member 53 to an appropriate position within the slot 54. The movement of the arm 48 causes a 65 turning movement of the trunnion 46 to

change the position of the axis of the grinding wheel spindle 11 which, as already noted, is eccentrically mounted in the trunnion 46, thereby causing the grinding wheel 12 to move cyclically towards and away from the other wheel. 70

The cam roller 71 (Fig. 7) is maintained in contact with the projection 73 and the radial face of the cam 72 by means of a spring (not shown). This causes a reciprocation of the arm 70 and the yoke 57 and consequently an axial reciprocation of the grinding wheel spindle 11, depending upon the shape of the cam face. In the machine illustrated in the drawings, the grinding wheel 12 is moved directly into the work preferably without axial oscillation. The cam 58 which moves the wheel into the work is so shaped as to give the grinding wheel a continuous feeding motion in a direction toward the work, and then at the end of this feeding motion to give a dwell to the wheel which allows any spring of the machine to be taken out and also allows a sparking out operation that tends to produce a better finish. It is preferably during the time that the grinding wheel is held against the work or during this period of dwell of the cam, that the grinding wheel spindle is oscillated. However, there is preferably only one oscillation; that is, while the grinding wheel is dwelling against the work it is moved about 1/8 of an inch away from the shoulder or head on the work, if grinding shouldered work, and again brought back to position. This tends 100 to take out any scratches or wheel marks on the work. 95

At the same time the cam 95 (Figs. 4 and 11) is rotated uniformly with the cam roller 98 in contact therewith, thereby causing oscillation of the arm 96, turning of the shaft 97, and oscillation of the arm 99 to move the rod 101 and cause oscillating movement of the member 75 to move the front work-holding member or blade 83 towards and away from the work holding member 34 between the wheels. It should be noted that, since the member 75 is pivoted to swing about a pivot shaft 76 which is horizontally disposed and parallel to the axis of the grinding wheel, the front work-holding member or blade 83 will always move through positions parallel to itself and to the work axis, inasmuch as the axis of the latter is parallel to the axis of the grinding wheel. I prefer 110 that its movements be parallel to itself for I am thereby enabled to achieve many thoroughly practical advantages. 115

The relative movement of the grinding wheel 12 and the front work-holding member 125 or blade 83 towards and away from the work W is illustrated in Figs. 8, 9 and 10. The normal position of the grinding wheel 12 and the front blade 83 is shown in Fig. 8 with the grinding wheel away from the work and the 130

front blade away from but in approximate contact with the work. Now when the lever 145 (Fig. 1) is moved to the left to connect power with the camshaft 59, the cams 58 and 95 are rotated so as to move the front blade 83 into contact with the work W, and so that the front blade 83 holds the work W against the work-holding member 34, and then bring the grinding wheel 12 into operative grinding contact with the work, as viewed in Fig. 9. After completion of the grinding operation the grinding wheel 12 moves away from the work and then the front blade 83 withdraws allowing the work to roll in the direction of rotation of the work regulating wheel 23 and be discharged, as indicated in Fig. 10.

The speed of the automatic movements above described may be increased or decreased by adjusting the belt 119 (Fig. 1) in appropriate position upon the cone pulleys 120 and 121. Thus, the work pieces may be ground at a most suitable rate depending upon the character of the work and such other variable factors as will now be readily understood by those skilled in the art.

The normal position of rest of the grinding wheel 12 and the front blade 83 when the automatic movements are stopped is that illustrated in Fig. 8. If it is desired to operate the machine automatically for one complete cycle and then stop with the front blade 83 and the grinding wheel 12 away from the regulating wheel, this may be accomplished by moving the lever 145 (Fig. 1) to bring the projection 153 (Fig. 5) on the rod 140 to a predetermined location within the path circumscribed by the projection 154 on the tripper cam 155.

It will be observed that with the tripper cam 155 in the proper position upon the cam-shaft 59 relative to the cams 58 and 95, that the front work-holding member or blade 83 and the movement of the grinding wheel 12 may be brought to a position of rest, such as is illustrated in Fig. 8, as the projection 154 comes in contact with the projection 153 to move the double link 136 and the clutch yoke to disengage the clutch 122 from the pulley 112.

It will be observed that the center of the eccentric trunnion 46 (indicated at the intersection of the lines A and C in Fig. 7) is between the center of the grinding wheel spindle 11 (indicated by the intersection of lines B and C) and the cam 58, and that the parts are so arranged that rocking movement of the trunnion moves the grinding wheel in the substantially vertical portion of an arc. The cam 58, as shown diagrammatically in Fig. 11, is so shaped as to cause the grinding wheel to move abruptly into an approximate grinding position and then gradually to grind the work, the wheel then being withdrawn quickly to its initial position. This cam may be shaped to give the type of operation desired,

but as illustrated it has a spiral face which, when rotated in the direction of the arrow (Fig. 11), moves the cam roller 57 from a point *a* to a higher point *b* to feed the wheel into the work. The grinding wheel then dwells upon the work while the cam roller 57 contacts with the portion between the points *b* and *c* which are substantially equidistant from the camshaft 59. From the points *c* to *d* on the cam 58, the cam roller 57 drops away rapidly and then climbs the incline *d*—*a*, thus moving the grinding wheel rapidly away from and then towards the work.

The cam 95 is so shaped and so located upon the shaft 59 relative to the cam 58 that the arm 75 will move the positioning blade 83 into approximate contact with work between the wheels when the grinding wheel is away from the other wheel, and into contact with the work during grinding, and then away from the work as the grinding wheel is moved away from the other wheel to permit discharge of ground work by rolling laterally in the direction of rotation of the work regulating wheel 23. As shown in Fig. 11, the cam roller 98 is shown in its position of rest *e* upon the cam 95. When the camshaft 59 is rotated, the roller 98 moves along the peripheral surface of the cam 95 from *e* to *f* and thereby causes the front guide blade 83 to move into contact with the work *w* (as shown in Fig. 9), and remains in that position until the roller 98 reaches the point *g*. The blade 83 is then caused to move away from the work while the roller passes from *g* to *h*, and into approximate contact with the work as the roller moves from *h* to *k* where it remains until the roller 98 reaches the point *e* where the cam 95 comes to a stop in position for repeating the cycle.

When the machine is operated automatically or semi-automatically as previously described, the work may be placed between the wheels by hand when the grinding wheel 12 and the front blade 83 are away from their operative grinding positions. But in accordance with my preferred practice, a manually controlled work conveying device of the type previously described is employed for feeding successive work pieces between the wheels in a position for grinding. Thus, when the lever 145 is moved to the left to engage the clutch 122, the rope 155 is moved simultaneously a definite distance at any desired rate to move the plunger 163 an invariable amount and thereby push a work piece, which has been placed by hand upon the work carrier 176, on the work regulating wheel 23 and between the rear blade 34 and the front blade 83 after the grinding wheel 12 and the blade 83 have moved to the position shown in Fig. 8. The lever 145 is then brought to the right to move the rod 140 downwardly so as to bring the projection 153 to an appropriate point within the path circumscribed by the

projection 154 so the movement of the grinding wheel towards and away from the other wheel, and the movement of the arm 75 towards and away from the work, will be brought to a stop in the position shown in Fig. 8 after completing the cycle. At the same time the spring 171 returns the plunger 163 to a position of rest against the screw 174 and into a position for receiving another piece of work which is to be fed between the wheels.

It will thus be seen that, in accordance with certain features of the invention a grinding machine is provided which is easily adaptable for grinding a large variety of cylindrical work, such as shouldered work, in a more economical and satisfactory manner than has heretofore been possible. Thus, regardless of the length, size or weight of the work piece to be ground, successive work pieces of the same type are brought to the same position between the wheels for grinding and held in that position by a movable work-holding member or blade which is in contact with the work throughout its entire length and maintains contact between the work and the rear work-holding member or blade, and assures that no irregularities will be formed upon the work due to a slight movement out of the most suitable grinding position. Furthermore, the successive work pieces are fed to the same grinding position between the wheels and the ground work discharged from the machine in a safe and most economical manner.

The terms "regulating wheel" and "slowly rotated regulating wheel" are to be construed in the now commonly accepted understanding of those skilled in the centerless grinding art. The speeds of both the grinding wheel and the regulating wheel must necessarily be varied in accordance with the type and nature of the work to be ground as well as the particular operation to be performed. The grinding wheel is to be rotated at a speed found suitable for grinding the work and the regulating wheel is to be given such a speed that the work will rotate during the grinding operation at that rate which is found desirable for the particular operation to be performed. Without reference to the theory of operation, the regulating wheel serves to control the speed of the work and is driven at such a slow speed that it determines the rate of rotation of the work, and the work may be given a faster or slower speed by increasing or decreasing the speed of the regulating wheel respectively; by "speed", I mean rate of rotation.

It will thus be seen that there has been provided in this invention an apparatus in which the several objects hereinabove noted, as well as many thoroughly practical advantages, are successfully achieved.

Certain features of the apparatus disclosed

in this application are broadly disclosed in, and claimed in the claims of, my co-pending application Serial No. 71,484, filed November 25, 1925.

As many possible embodiments may be made of the above invention and as many changes might be made in the embodiment above set forth, it is to be understood that all matter hereinbefore set forth or shown in the accompanying drawings, is to be interpreted as illustrative and not in a limiting sense.

Having thus described my invention, what I claim as new and desire to secure by Letters Patent is:

1. A grinding machine comprising a rapidly rotated grinding wheel and a slowly rotated work regulating wheel, means for holding work of round section between said wheels, said means including a relatively fixed member and a relatively movable member, the latter being movable toward and away from said first-mentioned member, and a mechanism constructed and arranged to move said second-mentioned members to positions parallel to the work axis into contact with the work to hold the work between itself and said other member during grinding and away from the ground work to permit discharge thereof.

2. A grinding machine comprising a rapidly rotated grinding wheel and a slowly rotated work regulating wheel, means for moving one of the wheels towards and away from the other, means including a movable blade for positioning the work in grinding contact with the wheels, and a mechanism constructed and arranged to move said blade to positions parallel to the work axis into approximate contact with the work while said movable wheel is away from the other and into contact with the work during grinding and then out of contact with the work to permit discharge thereof.

3. A centerless grinding machine comprising a rapidly rotated grinding wheel and a slowly rotated work regulating wheel, a member between said wheels for holding work of round section in operative relation thereto, a movable work engaging member to hold the work in operative relation with said work holding member during grinding, means to move the work axially into the grinding zone, and means for moving said work engaging member so as to permit the work to escape laterally from the grinding zone.

4. A centerless grinding machine comprising a rapidly rotated grinding wheel and a slowly rotated work regulating wheel, means for moving one of the wheels towards and away from the other, means including a blade adapted to move so as to position the work between the wheels for grinding and to move away from the ground work to permit discharge thereof, and a mechanism constructed and arranged to move a work piece

in an axial direction into a grinding position while the wheels are separated.

5. A centerless grinding machine comprising a rapidly rotated grinding wheel and a slowly rotated work regulating wheel, means for moving one of the wheels towards and away from the other, means therebetween for positioning work for grinding including a movable blade, a mechanism arranged to 10 move said blade to positions parallel to the work axis into approximate contact with the work while said movable wheel is away from the other and into contact with the work during grinding and then withdraw to permit discharge of ground work, and means operating in timed relation with said blade and wheel movements to move a work piece in an axial direction into a grinding position while the wheels are separated.
- 20 6. A centerless grinding machine comprising a rapidly rotated grinding wheel and a slowly rotated work regulating wheel, means therebetween for positioning work for grinding, means for moving one of the wheels towards and away from the other, a mechanism for moving work between the wheels in an axial direction, and a manual device to actuate said mechanism to move work into a grinding position while the wheels are separated.

- 30 7. A centerless grinding machine comprising a rapidly rotated grinding wheel and a slowly rotating work regulating wheel, means therebetween for positioning work for grinding, means for moving one of the wheels towards and away from the other, a mechanism for moving work between the wheels in an axial direction, and a manual control device for starting and stopping said wheel movements and adapted to actuate said mechanism to move work into a grinding position while the wheels are separated.

- 40 8. A centerless grinding machine comprising a rapidly rotated grinding wheel and a slowly rotated work regulating wheel movable relatively towards and from each other, means to maintain a work piece of round section in operative relation with said wheels, a manually controlled mechanism to feed a piece of work into the grinding zone at a desired rate, means operating in timed relation with said mechanism to cause the wheels to move through a single cycle relatively towards each other after the work is in position and to grind the same to a given size and thereafter separate.

- 50 9. A centerless grinding machine comprising a rapidly rotated grinding wheel and a slowly rotated work regulating wheel movable relatively towards and from each other, means to maintain a work piece of round section in operative relation with said wheels, a manually controlled mechanism to feed a piece of work into the grinding zone at a desired rate, means operating in timed relation

with said mechanism to cause the wheels to move through a single cycle relatively towards each other after the work is in position and to grind the same to a given size and thereafter separate, and means for automatically discharging the work from the grinding zone while the wheels are separated.

- 70 10. A centerless grinding machine comprising a rapidly rotated grinding wheel and a slowly rotated work regulating wheel, means for moving one of the wheels towards and away from the other, means including a blade adapted to move through parallel positions to position work between the wheels for grinding and permit discharge of ground work laterally, a mechanism for moving work between the wheels in an axial direction, and a manual control device for starting and stopping said wheel and blade movements and adapted to actuate said mechanism to move work into a grinding position while the wheels are separated.

- 80 11. In grinding apparatus, in combination, a four-sided grinding throat in which work of round section is received for simultaneous grinding and rotation, said grinding throat including a grinding wheel rotatable at relatively high speed, a regulating wheel rotatable at relatively low speed, said wheels being adapted to present adjacent operative surfaces traveling in opposite directions, a member for holding work in operative relation to said two wheels and adapted to take up the thrust of the grinding wheel on the work, and a member spaced from said first-mentioned member for taking up the oppositely directed thrust of the regulating wheel on the work; means for moving a work piece axially into said grinding throat; and means for moving one of said work holding members parallel to itself and away from the other, to permit discharge of a ground work piece from the grinding throat.

- 90 12. In grinding apparatus, in combination, a four-sided grinding throat in which work of round section is received for simultaneous grinding and rotation, said grinding throat including a grinding wheel rotatable at relatively high speed, a regulating wheel rotatable at relatively low speed, said wheels being adapted to present adjacent operative surfaces traveling in opposite directions, a member for holding work in operative relation to said two wheels and adapted to take up the thrust of the grinding wheel on the work, and a member spaced from said first-mentioned member for taking up the oppositely directed thrust of the regulating wheel on the work; means for relatively separating said two work holding members to permit the discharge of a ground work piece from said grinding throat and for relatively approaching said two members to hold a work piece in operative relation to said two wheels; and means operative prior to the completion of

the relative approaching movement of said two members for inserting a work piece in an axial direction therebetween.

13. In grinding apparatus, in combination, 5 a four-sided grinding throat in which work of round section is received for simultaneous grinding and rotation, said grinding throat including a grinding wheel rotatable at relatively high speed, a regulating wheel rotatable at relatively low speed, said wheels being adapted to present adjacent operative surfaces traveling in opposite directions, a member for holding work in operative relation to said two wheels and adapted to take 15 up the thrust of the grinding wheel on the work, and a member spaced from said first-mentioned member for taking up the oppositely directed thrust of the regulating wheel on the work; power actuated means for 20 changing the relation of said grinding throat to the work, and means operating in timed relation thereto for moving a work piece in an axial direction into the grinding throat.

14. In grinding apparatus, in combination, 25 a four-sided grinding throat in which work of round section is received for simultaneous grinding and rotation, said grinding throat including a grinding wheel rotatable at relatively high speed, a regulating wheel rotatable at relatively low speed, said wheels being adapted to present adjacent operative surfaces traveling in opposite directions, a member for holding work in operative relation to said two wheels and adapted to take up the 30 thrust of the grinding wheel on the work, and a member spaced from said first-mentioned member for taking up the oppositely directed thrust of the regulating wheel on the work; mechanism adapted in recurring sequence to relatively separate said two work 35 holding members and to relatively approach them; and means operating in timed relation to said mechanism for moving a work piece in an axial direction into said grinding throat prior to the completion of the relative 40 approaching movement of said two members, the relative separating movement of said two members being sufficient to permit the discharge of a ground work piece in a direction 45 transverse to the grinding throat.

15. In grinding apparatus, in combination, 50 a four-sided grinding throat in which work of round section is received for simultaneous grinding and rotation, said grinding throat including a grinding wheel rotatable at relatively high speed, a regulating wheel rotatable at relatively low speed, said wheels being adapted to present adjacent operative surfaces traveling in opposite directions, a member 55 for holding work in operative relation to said two wheels and adapted to take up the thrust of the grinding wheel on the work, and a member spaced from said first-mentioned member for taking up the oppositely directed 60 thrust of the regulating wheel on the work;

means for relatively separating and approaching said two wheels and for relatively separating and approaching said two work holding members; and means for moving a work piece in an axial direction into said 70 grinding throat prior to the completion of the relative approaching movement of the parts comprising said grinding throat.

Signed at Worcester, Massachusetts, this 16th day of Jan., 1926.

HAROLD W. HOLMES.
